(57) **CLAIM**

The ornamental design for the aerial refueling receptacle with raised fairing marking, as shown and described.

DESCRIPTION

FIG. 1 is a top, front and left side perspective view of an aerial refueling receptacle with raised fairing marking in accordance with the present invention;

FIG. 2 is a top perspective view thereof;

FIG. 3 is a front perspective view thereof; and,

FIG. 4 is a left side perspective view thereof; the right side perspective view being a mirror image thereof.

The broken line showing of an airplane in FIG. 1 is for the purpose of illustrating environmental structure only and forms no part of the claimed design. The broken line showing of an aerial refueling receptacle and a raised fairing in FIGS. 2-4 is for the purpose of illustrating environmental structure only and forms no part of the claimed design.

1 Claim, 3 Drawing Sheets
